US00D975889S

(12) **United States Design Patent** (10) Patent No.: **US D975,889 S**
Herrmann (45) Date of Patent: **** Jan. 17, 2023**

(54) **LAMP**

(71) Applicant: **Glatz AG**, Frauenfeld (CH)
(72) Inventor: **Denis Herrmann**, Winterthur (CH)
(**) Term: **15 Years**
(21) Appl. No.: **35/513,394**
(22) Filed: **Jul. 19, 2021**

(80) **Hague Agreement Data**

Int. Filing Date: **Jul. 19, 2021**
Int. Reg. No.: **DM/215603**
Int. Reg. Date: **Jul. 19, 2021**
Int. Reg. Pub. Date: **Jan. 21, 2022**
(51) LOC (14) Cl. **26-03**
(52) U.S. Cl. **D26/24**
USPC **D26/24**

(58) **Field of Classification Search**

USPC D26/24, 60, 67-70, 72, 80, 104, 118;
D10/106.6, 106.8
CPC F21S 8/032; F21S 9/02; F21V 21/088;
